ABSTRACT

A folding carton comprising a blank of sheet material folded to form a tube having at least one plane side wall and at least at one end of the tube an end wall. The end wall consists of a flap cut out in the plane side wall of the tube and folded an angle of 180° along a first fold line towards and beyond the end of the tube and then is folded along a second fold line to cover the end of the tube.

FOLDING CARTON CONSISTING OF A STRIP OF SHEET MATERIAL FOLDED TO FORM A TUBE AND PROVIDED WITH END WALLS

Folding cartons usually consist of a strip of sheet material folded to form a tube and provided with end walls consisting of flaps protruding beyond the longitudinal side edges of the substantial strip with respect to the folding direction of the strip, which flaps are folded to close the ends of the tube. Thus, a considerable waste of sheet material arises due to the fact that the total width of the strip including the flaps to a high degree exceeds the length of the tube, the cut away material of the strip intermediate said flaps constituting pure waste material. It is also known to use separate end walls attached to the ends of the tube as a substitute for protruding closure flaps. Thus an essential reduction of consumption of material is obtained, but a considerable technical complication is involved in handling and attaching said end walls. A certain saving of material can be obtained if the end walls are formed by U-shaped tongues cut from one of the side walls of the tube and folded inwardly 90° to cover the end openings of the tube and to abut against the inner surfaces of the tube at a distance from the ends of the tube. The width of the strip, however, cannot be fully used because projecting edges are formed at the ends of the folding carton, which edges form an unemployed space and a waste of material that cannot be eliminated. A further disadvantage is that the outer surfaces of the end walls of the ready-folded carton consist of the surface of the strip of material facing the interior of the tube when the tube is folded. Accordingly, the strip of material, as a rule, has to be glazed or printed on both surfaces. Moreover, the folded carton cannot be folded around an object to be packed but has to be finished before the object is inserted into the folded carton.

This invention relates to a folded carton consisting of a strip of sheet material having straight edges, for example a strip of boxboard, folded to form a tube having at least one plane side wall and at least at one end of the tube an end wall consisting of a flap cut out and folded from a plane side wall of the tube.

The object of the invention is the provision of a folded carton having the advantages of the known folded cartons but not their disadvantages, i.e., a folded carton which can be readily manufactured without any appreciable waste of material. Moreover, the folded carton should be suitable for being manufactured by a strip of sheet material obtained from a storage reel.

These objects are obtained by the folding carton according to the invention defined by the claims appended hereto.

The invention is characterized in that said flap is folded 180° along a first fold line towards and beyond one end of said tube and then is folded along a second fold line to cover this end of the tube. Thus, the folding carton can be finished without the end walls being folded to interfere into the interior of the folding carton, and the distance between the end walls of the folding carton is equal to the total width of the blank of sheet material, i.e., no dead space is formed at the ends of the folding carton. By dimensioning the width and length of the cut out flap larger than the cross section dimensions of the tube it is possible to provide the flap with edge portions which folded perpendicular to the plane of the flap apply against the outer surfaces of the side walls of the end of said tube. The opening formed by said flap cut out in the side wall or walls of the tube can be covered by an additional side wall of the tube so that a completely closed folded carton is obtained.

A very essential advantage of the folded carton according to the invention is that a strip of sheet material can be used being printed or having a surface treatment on only one side without the printed side of the end walls being turned inwardly.

A folded carton having the printed side of all side walls turned outwardly is accordingly obtained if the folding carton is designed as set forth in claim 4. An additional side wall of the tube covering the opening formed by the end wall flap may consist of a strip of preferably transparent material glued to the blank of sheet material, which strip can be glued to the

blank prior to the finishing of the folded carton. The glued strip can be positioned on the inside of the tube and be designed to form a bag-shaped lining in the tube. According to an embodiment of the folded carton according to the invention

- 5 a portion of the blank of sheet material can be folded to and fro between two opposing side walls and form a plurality of parallel compartments in the longitudinal direction of the tube. Also an embodiment of this kind is obtained without waste of material. The provision of compartments of this kind 10 in connection with known folding cartons having projecting end wall flaps is accompanied by an outrageously high consumption of material.

The invention will be better understood from the following description of various embodiments of folding cartons in accordance with the invention, in conjunction with the accompanying drawings.

FIG. 1 is a perspective view of a first stage of finishing of a folding carton.

- 15 FIGS. 2 to 3 illustrate, in perspective view, three different stages of the finishing of a folding carton.

FIG. 4 illustrates, in perspective view, a folding carton having an end wall provided with edge portions intended to be applied against the end portion of the tube,

- 20 FIG. 5 illustrates, in perspective view, a modification of the carton shown in FIG. 4 before the closing of the end of the tube,

FIGS. 6 and 7 illustrate, in perspective view, two embodiments of a carton in accordance with the invention and provided with interior compartments,

- 25 FIG. 8 illustrates, in perspective view, a modification of the carton shown in FIGS. 1 to 3,

FIGS. 9 to 12 illustrate, in plan views, an end view and a side view, respectively, different steps of the finishing of a carton 30 provided with lockable end flaps,

FIG. 13 is an end view of a carton having reinforced side walls, and

- FIG. 14 is an end view of a modification of the carton shown in FIGS. 9 to 12.

40 In FIG. 1 a tube is shown having a rectangular cross section and being formed by winding a strip of boxboard. The tube is provided with a top wall consisting of two walls 1, 2, two narrow side walls 3, 4 to which end portions 5, 6 of the strip are glued, and a bottom wall. Two flaps 7, 8 are cut out in the top wall 1 which flaps in FIG. 2 are shown folded back an angle of 180° beyond the ends of the tube and in FIG. 3 are shown folded down further an angle of 90° so that the flaps are positioned to cover the ends of the tube. At each end of the flaps 7, 8 a fold line 9, 10 is provided defining an edge portion intended to be folded in between the flaps and the inside of the bottom wall of the tube.

45 The folding carton shown in FIGS. 1 to 3 is especially suitable for packing frozen products since an edge 11, 12 protruding from the wall 2 is formed at each end of the carton permitting circulation of air between the cartons of a stack of cartons.

50 Since in many cases and especially in packing frozen products the content of the carton is airtight enclosed in a special bag, the wall 2 and the end portion 6 can be omitted in the carton shown in FIGS. 1 to 3, in which case an open-topped carton is achieved. The projecting folded edges 11 and 12 in this case form a reinforcement of the edges of the opening.

55 From FIGS. 1 to 3 is evident that the flaps 7 and 8 can be cut out from the lower wall 2. In this case, of course, the flaps are folded out before folding the wall 1 to the position shown in FIG. 1. The wall 1 and the end portion 5 can be designed as a hinged cover.

60 In order to achieve an improved tightening between the flaps 7, 8 and the ends of the tube the flaps 7, 8 suitably include a portion of the adjacent walls 4 and 5, as shown in FIG. 4. Thus, the dimensions of the flaps 7, 8 exceed the dimensions of the cross section of the tube so that edge portions 13 are formed which folded perpendicular to the planes of the flaps can be inserted along the insides of the walls of the end

portions of the tube. If desired, the wall 2 may be provided with a tear-off line so that a hinged cover is obtained in at least a part of the opening in the wall 1. As an alternative the edge portions 13 of these flaps 7, 8 can be joined at their corners and be pushed on the outsides of the end portions of the tube. A carton of this kind can be easily opened and closed by one of the flaps and is especially suitable as a cigarette packet.

FIG. 5 discloses an embodiment similar to the carton shown in FIG. 4 but having the wall 2 omitted and replaced by a strip 14 of for instance transparent material, which strip is glued to the inside of the tube and extends beyond the ends of the tube. The projecting end portions of the strip 14 can be provided with transversal seals and can be folded into the tube before the closing of the carton by means of the flaps 7, 8. If desired the strip may be arranged to cover only the end opening of the tube.

FIG. 6 illustrates an embodiment of the invention in which a very high saving of material is obtained. The folding carton consists of an elongated strip of material which is folded in a similar way as is shown in FIG. 1 but which extends from the end portion 6, shown in FIG. 1, in a plurality of curves 15 to and fro between the walls 3 and 4 to which walls the curved portions are glued so that a plurality of parallel, longitudinal compartments are formed in the tube. The ends of the tube are closed by flaps 7, 8 in the same way as is shown in FIGS. 1 to 3. If a closed carton is desired the provision of the flaps 7, 8 cause an increase of the length of the blank by the distance corresponding to the width of the flaps. If, on the contrary, the flaps are positioned, as priorly known, beyond the longitudinal side edges of the strip a considerable waste of material occurs due to the fact that all the material of the elongated strip between the projecting spaced flaps is lost. A similar waste of material occurs if the known carton is wended in the modified way shown in FIG. 7.

FIG. 8 illustrates an embodiment in which the double walls 1, 2 are formed by folding back the blank of sheet material in the direction contrary to the winding direction.

Although the folding cartons shown on the drawings have a rectangular cross section it is evident that the cartons can have various cross sections, provided a plane side wall is present in which the flap or flaps can be cut out.

FIG. 9 illustrates the unprinted side of a blank of boxboard cut from a web of material wound on a bobbin and having only one printed side. At the same time as the blank is cut from the web two end wall flaps 21, 22 are cut, which flaps are connected to the rest of the blank at the fold lines 23, 24.

The blank is divided by fold lines into a narrow side wall 25, a broad side wall 26, a narrow side wall 27, a broad side wall 28, a narrow side wall 29a, 29b, and a fastening flap 30. The fastening flap 30 is connected to the side wall 29a, 29b by two narrow strips 31, 32, which remain after the cutting of the end wall flaps 21, 22 and their side edges 33 and locking tongues 34. In FIG. 9 the end wall flaps 21, 22 are shown folded back beyond and eventually glued to the narrow strips 31, 32.

FIG. 10 illustrates the blank shown in FIG. 9 but folded along a central fold line on the side wall 29a, 29b at the same time as glueing is performed of the side portions applied against each other, which glued side portions are unprinted.

In FIG. 11 the narrow side wall 27 has been folded up perpendicular to the side wall 28, the broad side wall 26 has been folded in parallel to side wall 28, and the narrow side wall 25 has been folded down and glued against the folded-up side wall 29a. After folding of the edge walls 33 perpendicular to the end wall flaps 21, 22 and joining of the corners of said edge walls in a suitable way, the end wall flaps 21, 22 can be folded against the ends of the carton and at the same time the locking tongues 34 can be inserted into slots 35 in the narrow side walls 25, 27, as shown in FIG. 12.

Additionally or as an alternative locking tongues 34 may be arranged at the remaining edge wall of the flaps 21, 22 and inserted into slots in the broad side wall 26. This is possible if a strip of waste material arises in an interspace between the flaps 21, 23 at cutting these flaps and their edge walls 33. If

not, a locking tongue 34 of one of the end wall flaps is to be cut from the adjacent edge wall of the other end wall flap, and the reverse, which decreases the stiffness of the end wall flaps.

Eventually, the locking tongues of at least one of the end wall flaps may be omitted and a corresponding locking be obtained by glueing or merely by spring action.

Especially at large cartons it may be suitable to use double side walls, as shown in FIG. 13, to obtain an increased stiffness of the narrow side walls which may be required when cartons 10 are stacked lying one on the other. In order to have the visible joint between wall 26 and the double walls 29a, 29b positioned at an edge of the carton it is suitable to position the wall 25 on the inside of wall 29b in order to avoid waste of material. Any 15 additional glueing beside the corners of the edge walls 33 of the flaps 21, 22 is not necessary, especially if the flaps are provided with locking tongues 34 which suitably are inserted into slots 35 extending through the double side walls.

If an open-topped carton is desired the side walls 25, 26 in 20 FIGS. 12 and 13 can be omitted. The narrow side walls are in this case supported by the edge walls 33 of the flaps 21, 22 and, eventually, by the locking tongues 34.

The invention is not limited to the embodiments shown and 25 described but further modifications are possible within the scope of the invention defined by the accompanying claims, and other types of material than boxboard can be used, e.g., corrugated cardboard. Moreover, the side wall 25 of the carton shown in FIG. 13 can extend to and fro between the narrow side walls down towards the side wall 28 to form compartments in the interior of the carton. In this case the necessary stiffness is obtained, as a rule, without using double side walls, and, hence, the carton can have the shape shown in FIG. 14 which in principle does not differ from the carton shown in FIGS. 9 to 12.

35 In a simple embodiment of the invention the opposed edge walls 33 of the end wall flaps 21, 22 can be omitted. As an alternative the remaining edge wall 33 at the end of the end wall flaps can be omitted or folded and glued against the flaps 21, 40 22. This is suitable in connection with an open-topped carton, or if the side wall 26, preferably in the embodiment shown in FIG. 13, should be used as a hinged cover.

What is claimed is:

1. A folding carton consisting of a blank of sheet material 45 having straight edges and folded to form a tube having opposite planar side walls and at least one end wall, one of said side walls being constituted by two overlapped thicknesses of material, said end wall being formed by a flap cut out and folded from one of thicknesses of material of said one side wall, said flap being folded 180° along a first fold line towards and beyond one end of said tube and then folded along a second fold line to cover this end of the tube, said flap when folded from the thickness of material forming an opening in said thickness of material which is covered by the other thickness of material of said side wall.

2. A folding carton as claimed in claim 1, wherein the length and width of said flap (7,8) exceed the cross section dimensions of the tube, the flap being provided with edge portions (13) folded perpendicular to the plane of said flap and applied 50 against the outer surfaces of the side walls of the end of said tube.

3. A folding carton as claimed in claim 1, wherein the blank of sheet material is printed on only one side, the blank of sheet material being double-folded with the printed side turned out and so that a portion (21,22,29b,30) of the blank extends along at least a part of the remaining blank, in addition to which the end wall flap (21,22) or each flap is formed by a part of the blank portion (21,22,19b,30) of the double-wall 65 portion of the folding container which has a printed side facing the interior of the folding container.

4. A folding carton as claimed in claim 3, wherein the end wall flap (21,22) or each flap is provided with locking tongues (34) inserted into slots (35) of at least one of the adjacent side walls (25,27) of the folding container.

5. A folding carton as claimed in claim 1, wherein said other thickness of material of said side wall consists of a strip (14) of preferably transparent material glued to the blank of sheet material.

6. A folding carton as claimed in claim 5, wherein said strip (14) attached by glueing is positioned on the inside of the tube and is adapted to form a bag-shaped lining in the tube.

7. A folding carton as claimed in claim 1, wherein said other thickness of material of said side wall consists of an extension (1 or 2) of the blank of sheet material in the folding direction of the tube.

8. A folding carton as claimed in claim 7, wherein said other

thickness of material of said side wall (2,14) is positioned on the inside of the tube.

9. A folding carton as claimed in claim 7, wherein said other thickness of material of said side wall (1) is positioned on the outside of the tube and is designed as a hinged cover.

10. A folding carton as claimed in claim 1, wherein the tube is provided with two opposing plane side walls (3,4), a portion (15) of the blank of sheet material being folded to and fro between said opposing side walls (3,4) forming a plurality of 10 parallel compartments in the longitudinal direction of the tube.
